UNITED STATES PATENT OFFICE.

HOWARD L. BUDD, OF BROOKLYN, NEW YORK, ASSIGNOR TO FRIEDMAN SILVER CO., INC., OF BROOKLYN, NEW YORK, A CORPORATION OF NEW YORK.

DESIGN FOR A CUP OR SIMILAR ARTICLE.

Application filed March 5, 1928. Serial No. 25,705. Term of patent 7 years.

To all whom it may concern:

Be it known that I, HOWARD L. BUDD, a citizen of the United States, residing at the borough of Brooklyn, city and State of New York, county of Kings, have invented a new, original, and ornamental Design for a Cup or Similar Article, of which the following is a specification, reference being had to the accompanying drawing, forming part thereof.

Fig. 1 is a top plan view of a cup embodying my new design,

Fig. 2 is a front view of the same.

I claim:

The ornamental design for a cup or similar article as shown.

HOWARD L. BUDD.
